UNITED STATES PATENT OFFICE.

JOSEPH FRANCIS DONNELLY, OF LEMONT, ILLINOIS.

STILL OR THE LIKE.

Application filed January 25, 1926, Serial No. 83,546. Renewed December 10, 1928.

This invention relates to an apparatus for the conversion of hydrocarbon oil. More particularly it relates to a type of apparatus known as a cracking still which is adapted 5 to treat hydrocarbon oils under high pressure and heat.

An object of my invention is to provide an apparatus capable of applying heat generated by combustion to a material which is 10 preferably of a refractory nature and capable of absorbing said heat and emitting it in the form of radiant heat in such a manner as would raise said material to the temperature capable of effecting an intense radiancy, 15 but reducing the temperature by absorbing a part of the heat transmitted to said material by heat interchange with a heat-absorbing fluid and subsequently effecting a heat interchange between the heat-absorbing fluid and the fluid which it is desired to finally heat.

A further object is to provide a structure capable of thoroughly mixing said heat-absorbing fluid with the gases of combustion 25 so as to effect a heat interchange therewith and subsequently effect a heat interchange between said mixture and the fluid it is desired to finally heat.

A further object is to provide a structure 30 capable of effecting heat interchange between the gases of combustion and said heat-absorbing fluid before they are brought into physical contact with each other in such a manner as to raise the temperature of said 35 heat-absorbing fluid to such a degree as will cause it to rise by convection with the gases of combustion.

A further object is to provide a structure 40 which will separate the gases of combustion and heat-absorbing fluid into a plurality of individual streams and effect a heat interchange between said gases and fluid by simultaneous, prolonged and separate contact with a heat-conducting material and subsequently bring said gases and fluid into physical 45 contact and intermixture, and subsequently applying the heat of said intermixture to the means containing the fluid to be finally heated in an even and prolonged contact therewith.

The accompanying drawings are illustrative of an embodiment of my invention, in which—

Figure 1 is a side elevation partly in cross 55 section of my apparatus;

Fig. 2 is a cross section on line 2—2, Fig. 1;

Fig. 3 is a cross section on line 3—3, Fig. 1. 1 are the side walls of the still which in the form shown is a cracking still used in connection with conversion of hydrocarbon oils. 60 2 are combustion chambers which are of the oil burning type. Oil burners are located at 3 which are inserted through passages 4. Air ducts 5 enter through the side walls 1 and lead underneath the combustion chambers 2 65 and discharge into passages 4. By this construction the air passes through ducts 5, and receives a preliminary heating and also absorbs heat from the bottom of the combustion chambers that would otherwise be dissipated and lost. Arches 6 are located at the 70 top of combustion chambers 2 which are provided with a plurality of passages 7 through which the gases of combustion pass. Above these arches 6 are a plurality of pairs of vertical walls 8 spaced so as to form passages 9 therebetween. Cross passages 10 at the upper end of the walls 8 intersect the passages 9. Cap pieces 11 are located on the top of the walls 8 which form the top walls of the 80 passages 10 and extend beyond the walls 8. The passage 9 is sealed at the bottom of the walls 8 by part 12 of the arches 6. Passages 7 through the arches 6 communicate with the 85 passages 13 formed between the pairs of walls 8. The cap pieces 11 are of such a size as to extend partly across the passages 13 leaving outlets 14 from the passages 13. The cross passages 10 communicate with the 90 passages 13 at a point below the cap pieces 11. 95 Chambers 15 are located in the side walls 1 which are supplied with air through the valve-controlled inlets 16. Steam or any desirable heat-absorbing fluid may be applied to the chambers 15 through the valve-controlled inlets 17. By manipulation of the 100 valves in the inlets 16 and 17 either of said sources of supply may be used separately or combined as desired. A series of passages 18 lead from the chambers 15 through the walls 1 to the lower ends of the passages 9 with which they communicate at the points 19. Control valves 20 are located in the passages 18. The arches and walls as described are 105 preferably formed of refractory material in the shape of bricks or slabs as shown.

The mixture of heat-absorbing liquid and gases of combustion is delivered from the outlets 14 into the chamber 21 in the upper part of which is located a continuous coil 22 110 through which the fluid which it is desired to heat passes. In the apparatus herein shown

the structure is duplicated on both sides of the wall 23 as shown in Fig. 1. The coil 22 extends above the combustion chambers in both sections and is centrally supported by the 5 wall 23. The coil 22 is comprised of a plurality of tubes connected at the ends by return bends 24. The heated mixture of gases and fluid is caused to follow a tortuous path through the layers of tubes by means of a series 10 of baffle plates 25 projecting from the side walls 1 in an alternate fashion. By this structure the hot gases and fluid are held in contact with the tubes for a sufficient length of time to effectually transmit their heat 15 to the fluid within the tubes.

For the purpose of conserving the heat for effective use within my apparatus, I employ a heat-insulating lining 28 combined with dead air spaces 29 in the side walls 1.

20 In operation the combustion in chambers 2 would normally heat the arches and superimposed walls to a temperature sufficient to emit an intense radiant heat, but the introduction of the heat-absorbing fluid into and 25 through the passages 9 absorbs the portion of said heat from the arches 6 and walls 8 by a prolonged contact therewith, thus reducing their temperature so as to cause a reduction 30 of the radiant heat which would otherwise be emitted therefrom. The gases of combustion and heat-absorbing fluid are physically mixed at the intersection of passages 10 with the passages 13 and after emerging from the outlets 14 are discharged into the lower portion 35 of the chamber 21 wherein they undergo a thorough heat interchange and intermix- 40 ture before arriving in contact with the coil 22. The heated mixture then passes around the convolutions of the coil 22 imparting heat therefrom to the fluid contained therein in an even and efficient manner.

45 My apparatus has the particular advantage that in place of intense radiant heat being applied to the lower rows of tubes of the coil 22 in which the fluid therein cannot absorb the desired amount of heat in the short space of time it takes in passing through said lower rows, it is transmitted to a large volume of fluid which passes around all of the 50 tubes comprising the coil and imparts its heat thereto in an even and efficient manner. This construction is particularly advan- 55 tageous in the heating of a decomposable fluid such as a hydrocarbon oil, since direct application of intense radiant heat causes a local overheating with consequent total decom- 60 position of the oil, which is avoided by my apparatus.

Having described my invention, what I 60 claims is:—

1. In an apparatus of the class described the combination of a combustion chamber, means for generating heat by combustion therein, said chamber having a top provided 65 with passages therethrough, a plurality of

pairs of separated walls extending upwardly from said top of said chamber forming passages between said pairs which passages connect with said passages through said top so as to allow the gases of combustion to 70 pass therethrough, said separated walls of each pair being spaced from each other so as to form a passage therebetween adapted to allow a flow of heat-absorbing fluid there- 75 through, and a passage at the top of each pair of walls adapted to conduct said heat-absorbing fluid into said gases of combustion.

2. In an apparatus of the class described the combination of a combustion chamber, means for generating heat by combustion 80 therein, said chamber having a top pro- 85 vided with passages therethrough, a plu- rality of pairs of separated walls extending upwardly from said top forming pas- 90 sages between said pairs which connect with said passages through said top so as to allow the gases of combustion to pass therethrough, top pieces positioned on the top of each pair of walls extending partly across the passages between said pairs of walls, said separated walls of each pair being so spaced from each other as to form a pas- 95 sage therebetween adapted to allow a flow of heat-absorbing fluid therethrough and a pas- 100 sage at the top of each pair of walls adapted to conduct said heat-absorbing fluid into said gases of combustion prior to their escape through the openings between said cap pieces.

3. In an apparatus of the class described the combination of a combustion chamber 100 having side walls provided with passages there- 105 in, and a top wall having passages therethrough adapted to allow the escape of the gases of combustion from said combustion chamber, a structure superimposed on said top wall of said combustion chamber com- 110 prising a plurality of separated walls form- 115 ing sets of passages therebetween, one set of passages being connected to said passages in said top wall of said combustion chamber and another set being connected to said pas- 120 sages in said side walls, means for supplying a heat-absorbing fluid to said passages in said side walls and connected passages in said structure, said structure being provided with 125 passages adapted to conduct said heat-absorbing fluid into said gases of combustion, and means for conducting the mixture of combustion gases and heat-absorbing fluid thus formed into heat-exchanging contact with a fluid to be heated.

4. In an apparatus of the class described the combination of a combustion chamber having side walls extending upwardly there- 125 from, said side walls having a plurality of chambers therein and a plurality of passages extending upwardly from said chambers, said combustion chamber having a top wall pro- 130 vided with passages therethrough adapted to allow the escape of the gases of combustion

- from said combustion chamber, a structure superimposed on said top wall of said combustion chamber comprising a plurality of separated walls forming sets of passages 5 therebetween, one set of passages being connected to said passages in said top wall and another set being connected to said passages leading upwardly from said chambers in said side walls, means for supplying heat-absorbing fluid to said chambers and passages in said side walls and connected passages in said structure, said structure being provided with passages adapted to conduct said heat-absorbing fluid into said gases of combustion, and 10 means for conducting the mixture of combustion gases and heat-absorbing fluid thus formed into heat-exchanging contact with a fluid to be heated.
5. In an apparatus of the class described 20 the combination of a combustion chamber having side walls extending upwardly therefrom, said side walls having a plurality of chambers therein and a plurality of passages extending upwardly from said chambers having fluid-controlling valves therein, said com- 25 bustion chamber having a top wall provided with passages therethrough adapted to allow the escape of the gases of combustion from said combustion chamber, a structure superimposed on said top wall of said combustion 30 chamber comprising a plurality of separated walls forming sets of passages therebetween, one set of passages being connected to said passages in said top wall and another set being connected to said passages leading up- 35 wardly from said chambers in said side walls, means for supplying heat-absorbing fluid to said chambers and passages in said side walls and connected passages in said structure, said structure being provided with passages 40 adapted to conduct said heat-absorbing fluid into said gases of combustion, and means for conducting the mixture of combustion gases and heat-absorbing fluid thus formed into heat-exchanging contact with a fluid to be 45 heated.

Signed at Chicago, Illinois, this 18th day of January, 1926.

JOSEPH FRANCIS DONNELLY.
